UNITED STATES PATENT OFFICE.

WILLIAM J. BRENNAN, OF SWAMPSOFT, MASSACHUSETTS, ASSIGNOR TO COIN SORTING AND COUNTING COMPANY, OF BOSTON, MASSACHUSETTS, A CORPORATION OF MASSACHUSETTS.

DEVICE FOR OPERATING UPON COINS.

Application filed June 18, 1920. Serial No. 390,002.

To all whom it may concern:

Be it known that I, WILLIAM J. BRENNAN, a citizen of the United States, residing at Swampscott, in the county of Essex and State of Massachusetts, have invented certain new and useful Improvements in Devices for Operating Upon Coins; and I do hereby declare the following to be a full, clear, and exact description of the invention such as will enable others skilled in the art to which it appertains to make and use the same.

The present invention relates to devices for operating upon coins or other articles of disk form and various sizes and more particularly to machines for separating coins from an indiscriminate mass, sorting them according to size, and delivering them separately to suitable receptacles.

One object of the invention is to provide certain new and useful improvements in devices of the above named general character tending to simplify their construction and to more efficiently control the movements of the coins, thereby preventing the coins from becoming disorderly and insuring that all coins of the same denomination shall be segregated, from those of different denominations.

To the accomplishment of this object, and such others as may hereinafter appear, the invention consists in the novel features of construction and arrangement of parts hereinafter described and claimed, the advantages of which will be apparent to those skilled in the art, from the following description.

In the accompanying drawings, illustrating the preferred embodiment of the invention, Figure 1 is a top plan view of the improved device; Fig. 2 is a sectional view taken on the line 2—2 of Fig. 1; Fig. 3 is a sectional view taken on the line 3—3 of Fig. 1; and Fig. 4 is a sectional view taken on the line 4—4 of Fig. 1.

In accordance with the present invention, a mass of coins of various denominations is operated upon by a separating device 6, whereby the mass is separated into individual coins and the coins delivered successively into the upper end of an inclined sorting chute 8. The chute 8 is so constructed and arranged that the coins roll on edge down the chute and are selectively diverted

according to size through a series of openings 10 (Figs. 2 and 3) in one of the side walls thereof, into a series of secondary chutes 12, each of the latter leading to one of a plurality of collecting tubes or receptacles 14, as shown in Fig. 1.

The separating device 6 is provided with a pocket or receptacle 16 for receiving the coins to be sorted, and an inclined rotary distributing or separating plate 18, which forms one side of the coin pocket 16, and operates to separate the coins from the mass in the pocket and deliver them successively into the sorting chute. The separating device 6 is similar in construction and mode of operation to that of the separating device illustrated, described and claimed in a copending application, Serial No. 269,145, filed Dec. 31, 1918, by John E. Doldt, and the mechanism for rotating the distributing plate may be similar to the mechanism employed for the same purpose in said application. As set forth in the application referred to, the inclined distributing plate 18 is mounted upon a stationary disk-shaped head 20 which is partially surrounded by a peripheral coin retaining wall 22, and said plate is provided with a plurality of radiating feed strips or ribs 24 which serve to separate the coins from the mass in the coin pocket as the plate rotates. A peculiarly shaped curved wall 26, similar in contour to that of the corresponding part in the device of the aforesaid application, is an extension of the wall 22 and serves, in conjunction with the distributing plate, to form the pocket 16 in which the coins are received.

As also described in the aforesaid application, a series of shallow grooves 28 are formed in the distributing plate, concentric with the periphery thereof, and a series of small pointed prongs 30 project from the curved wall 26 into the grooves for the purpose of dislodging from the face of the distributing plate any coins which may tend to adhere thereto. In the present device, in addition to said prongs, there are also provided a plurality of pins 32 (Figs. 1 and 4) which project from the lower edge of the curved wall 26 into the grooves 28 and serve to prevent any coins from passing from the coin pocket 16 downwardly beneath the wall 26. In the present construction, also, the distributing plate 18 is rotated in a clock-

wise direction, instead of in a counter-clockwise direction, as described in the prior application, in order that the coins may be introduced into the sorting chute substantially 5 in the direction of the length of the chute so as to avoid any tendency of the coins to rebound from the chute. As the separating device operates, all of the coins eventually 10 come into contact with the coin-retaining wall 22, and slide along the lower edge of this wall until they reach the lower end thereof, whereupon they are discharged directly into the sorting chute.

The sorting chute 8 comprises a floor portion 36 and opposite side walls 38, and is made sufficiently narrow to insure that the 15 smallest coins will be supported on edge therein. Throughout the greater portion of its length, the chute 8 is straight but near 20 the entrance end thereof the chute is curved, as shown in Fig. 1, and extends substantially one-third of the way around the supporting head 20, terminating at the lower extremity of the coin retaining wall 22. The chute is 25 arranged with its side walls disposed in planes oblique to the plane of the face of the distributing plate and the upper edge of the inner side wall of the chute adjoins the marginal portion of the head 20 between the 30 lower end of the coin retaining wall 22 and the curved side wall 26 of the coin pocket. To prevent the coins from passing too rapidly down the chute so that they might possibly be improperly sorted, the portion of the 35 sorting chute adjacent its curved upper end is inclined at a slightly less angle than the remaining straight portion of the chute, as indicated in Fig. 2, and thus retards somewhat the speed of the coins.

40 The coins of the largest size or denomination among those delivered to the sorting chute are guided by this chute directly into a suitable receptacle (not shown) which is provided to receive them. All the smaller 45 coins, however, must be segregated from the largest ones and those of each denomination must be segregated from the others. With this end in view there is an opening 10 provided in the sorting chute for each denomination of coins to be operated upon except 50 the largest, each opening 10 connecting the sorting chute with a separate secondary chute 12, and in order that the coins in passing down the sorting chute may be diverted 55 laterally by gravity through the openings 10 into the secondary chute, the sorting chute is inclined transversely, as well as longitudinally, as shown in Fig. 3. The angle of transverse inclination and the width 60 of the sorting chute are made such as to render it impossible for even the smallest of the coins operated upon to stand in an erect position as it rolls down the chute. Consequently, the coins will pass down the chute 65 with one face thereof resting upon the lower-

most of the transversely inclined side walls and will be caused to fall by gravity through one or another of the openings 10 and then to slide flatwise down the secondary chute. As shown in Fig. 2, the openings 10 are elongated in the direction of the length of the chute and each is made just sufficient in width to permit the passage therethrough of a particular denomination of coins, the 70 smallest opening being located nearest the entrance end of the chute and the openings growing progressively larger toward the opposite end thereof. Thus the dimes or the 75 smallest coins will be diverted through the first of the openings 10 while next in order 80 will be diverted the pennies, nickels, quarters and half dollars, while the dollars may pass directly from the sorting chute into a suitable receptacle as hereinbefore described, said receptacle being located beyond 85 the last secondary chute.

In order to prevent the escape through any of the openings 10 of coins which are of a diameter greater than the width of said 90 openings, the lower edges of these openings are located slightly above the floor of the sorting chute, as shown in Fig. 3. With the openings 10 thus located, the portion of the side wall of the chute just beneath each of 95 said openings constitutes a shoulder 40 which engages the faces of the coins as they roll down the chute across said openings and prevents the lower portions of the coins from being diverted outwardly through the opening. In the absence of such a shoulder 100 beneath each opening 10, the coins would be displaced by gravity, bottom edge first, so that they would project obliquely through the opening 10, in which event the coins 105 would strike against the end of the opening and be deflected therethrough and into the secondary chutes associated therewith, and while thus projecting obliquely through the opening their upper edges would interfere 110 with the free passage of coins through the main chute. By means of the above described construction, however, any tendency of the coins to be thus displaced and deflected into the secondary chute is avoided. Not only are the coins thus prevented from 115 being diverted into the wrong secondary chutes but, they are caused to tip top edge foremost through the openings 10 so that they will block the main chute.

Certain foreign coins which do not correspond in size with the coins upon which the device is designed to operate are liable to be 120 present in the mass of coins which are deposited in the device. In order to prevent such coins or any other coins of odd sizes 125 which might for any reason be improperly sorted into a secondary chute, from being delivered into the corresponding collecting tube, together with the properly sorted coins, provision is made for eliminating such 130

- improperly sorted coins from the secondary chutes. To this end each secondary chute is provided with an elongated opening 42 through which such coins may escape. 5 These openings 42 are centrally located transversely of the secondary chutes so that all coins properly passing through said chutes will pass over the openings without falling therethrough. Smaller coins, however, being unsupported when they reach the openings 42 will be eliminated from the chute. The coins which are thus eliminated from the secondary chutes fall into an inclined tray or chute 44 which extends transversely beneath said openings, and by means of which the discarded coins may be guided into a suitable receptacle (not shown).
- The collecting tubes 14 into which the properly sorted coins are delivered by the secondary chutes are supported upon a table 46, to form a series of upright magazines, each adapted to contain a stack of coins of a single denomination. The coins which are assembled in the collecting tubes 14 may be fed from the bottom of the tubes to counting devices and thereafter delivered to bank packages, if desired, or they may be used directly from the collecting tubes for making change or for any other purpose.
- The present device is useful wherever it is desirable to effect the sorting of coins according to size from an indiscriminate mass and to distribute the sorted coins to suitable receptacles. The coins are introduced into the sorting chute 8 in such a manner that they continue to travel in a direction which is substantially a continuation of their direction of movement in the separating device just before entering the sorting chute. Moreover the speed with which the coins travel is carefully regulated by the pitch of the chute so as to prevent the coins from moving too fast and thus possibly being prevented from passing through the proper opening 10. Consequently there is no tendency for the coins thus introduced into the chute to rebound or to move out of rolling contact with the floor of the chute, or out of sliding contact with the lowermost side wall thereof, as they pass through the chute. It is therefore unnecessary to employ any special devices for insuring the orderly behavior of the coins in the sorting chute. The coins fall gently through the openings 10 until they lie flat upon the floor of the secondary chutes and there is no tendency for them to rise out of their reclining position as they slide through these chutes, and accordingly no additional provision need be made to prevent disorderly behavior of the coins in said chutes.
- It will be seen that the device is extremely simple in construction and mode of operation, having no parts liable to get out of order or interfere with the free passage of
- the coins through the device. The device may be relied upon to deliver to the collecting tubes only coins of the proper denomination since any possible inaccuracy in the sorting is rectified by the elimination from the secondary chutes of any improperly sorted coins.
- It is preferred to provide for the automatic replenishment of the supply of coins in the coin pocket 16 of the separating device at regular intervals by means of apparatus such as that disclosed in the hereinbefore mentioned application, Serial No. 269,145. As therein illustrated and described, a main supply hopper 50 is provided into which the mass of coins to be operated upon is deposited by the attendant. A plunger 52 reciprocates vertically through the hopper 50, intermittently elevating small members of coins from the mass in the hopper and discharging them through a lateral opening 54, adjacent the top of the hopper, into a downwardly inclined chute 56 which discharges the coins into the coin pocket 16.
- While it is preferred to embody the invention in a device having the specific construction and arrangement of parts herein shown and described, it will be understood that such construction and arrangement is not essential except so far as specified in the claims and may be changed or modified without departing from the spirit and true scope of the invention.
- The invention having been described, what is claimed as new is:—
1. A machine for operating upon coins having, in combination, a coin separating device comprising an inclined rotary distributing plate, a stationary wall adjacent the uppermost face of said plate constructed and arranged to retain a mass of coins in fixed location relatively to the rotating face of the plate, a plurality of feed strips on the plate adapted to pass under the wall as the plate rotates and to engage certain of the coins to separate them from the mass, a plurality of grooves in the uppermost face of the plate concentric with the periphery thereof, and a plurality of pins projecting downwardly from the lower edge of said stationary wall into said grooves to prevent any of the coins of the mass from escaping downwardly beneath said stationary wall.
  2. A device for operating upon coins having, in combination, a longitudinally inclined main coin chute having an opening formed in the side thereof, the chute being tilted transversely to cause coins of a predetermined size to be diverted by gravity through said opening, and a secondary chute connected with the main chute through said opening, said secondary chute being provided with an opening for the elimination of coins improperly diverted into said chute.

WILLIAM J. BRENNAN.
